UNITED STATES PATENT OFFICE.

PLINY F. HODGES, OF OLD OFFICE, VIRGINIA.

ROTARY ENGINE.

No. 906,425.

Specification of Letters Patent.

Patented Dec. 8, 1908.

Application filed October 22, 1908. Serial No. 459,009.

To all whom it may concern:

Be it known that I, PLINY F. HODGES, residing at Old Office, in the county of Goochland and State of Virginia, have invented a new and Improved Construction of Rotary Engine, of which the following is a specification.

This invention relates to rotary engines and has for its purpose to provide an improved means of utilizing the expansive force of steam in rotary engines, and it consists in parallel steam passageways between the inlet and exhaust ports and valve mechanism operating to admit and cut off the steam to said passage ways alternately, so that the initial pressure from the boiler will be applied to one of said passages while the expansive force of steam is operating in the other passage way.

In its more subordinate features, my invention consists in certain details of construction and peculiar combination of parts, all of which will be hereinafter fully described, specifically pointed out in the appended claims and illustrated in the accompanying drawings, in which:

Figure 1, is a perspective view of my improved construction of rotary engine. Fig. 2, is a vertical, longitudinal section thereof. Fig. 3, is a horizontal section of the casing, the rotary piston or runner being omitted. Fig. 4, is a plan view of the rotary piston or runners. Fig. 5, is a perspective view of the rotary valve.

In the practical arrangement of my invention, the same is arranged as shown in Figs. 1 to 4 inclusive, and comprises a circular casing 1, which rises vertically from the base or foundation 10 integral with the casing and suitably flanged whereby it can be conveniently and solidly secured to a floor or other support. Within the casing is rotatably mounted the piston 2, which is keyed to the shaft 4 that journals in hub bearings 5^a—5^a on the cap plates 5 that form the end closures for the casing 1, to which they are held, steam tight, by the cross bolts 6—6, as clearly shown in the drawings. The cylinder casing 1 has centrally disposed exhausts x—x that are transversely disposed and discharge into a central exhausting port x', and at one side the said casing has a pair of transverse in-

lets 70^a—70^b that discharge into the casing and which communicate with a single valve chamber 7 in which is rotatably mounted the valve 8 and with which the feed pipe from the boiler connects.

The valve 8, the detailed construction of which is shown in Fig. 5, is formed with a central annular steam space 8^a and at each end with a number of equi-distantly spaced channels 81 that extend in the longitudinal axis of the valve and an equal number of cut offs 82, said cut offs and the channels in the opposite ends of the valves being alternately arranged whereby to provide for a proper co-operation of the valve with the steam passages in the casing and particularly for admitting the steam intermittently and alternately through the feed ports or inlets 70^a—70^b as best shown in Fig. 3.

The rotary piston 2 has its peripheral faces provided with two sets of parallelly disposed radial abutments 2^a, nine being shown in the drawings, that are joined by a series of peripheral passage ways or pockets 2^b that gradually but uniformly increase in depth in the forward direction, that is, in the direction of rotation of the piston, for reasons presently explained.

The two sets of passage ways or pockets in the manufacture of the piston and the casing are cored out and the said two sets form two continuous rows of steam passages that are interrupted at predetermined intervals by the abutments 2^a and 3^a, the said pockets or passage ways, as will be best seen from Fig. 4, do not extend entirely across the piston faces but are stopped short of the ends and of each other whereby to provide end closure portions 2^c and a central closure portion 3^c for the pockets or ways to hold the steam from passing against the end caps 5—5, or from one passageway to the other, the said two sets of pockets also being of a width equal that of the length of the steam inlets 70^a in the bottom of the casing.

The circular casing has two series of annularly disposed radial abutments 3^a that extend crosswise the distance equal the width of the two sets of pockets or passage ways on the piston and the said abutments 3^a gradually increase in depth from the infeed

end to the exhausting end of the casing, and they are joined by a series of longitudinally extending pockets 30 that gradually decrease in depth from the infeed to the exhaust side, as clearly shown in Fig. 2, from which it will also be noticed that the ends of the pockets in the casing are closed by the solid portions 30^a—30^b of the casing, so as to hold the steam from passing endwise out of the said pockets 10 30—30.

By arranging the pockets or steam passages on the piston and on the casing in the manner shown and described, the space between the casing wall and the piston is 15 most restricted at the infeed end and is of gradually increasing area toward the exhausts x, whereby to provide for taking proper care of the expansive force to prevent any back lash or cushioning of the said force, 20 since by reason of the gradually increasing depth of the casing surfaces practically all of the back pressure of the expansion force is taken up by the said abutments, thereby causing the said expansive force to exert a 25 maximum pressure against the abutments on the down-going side of the piston.

It will be noticed that by the peculiar construction and relative arrangement of the pockets or steam passages on the piston 30 and in the opposing casing wall, that at intervals the steam after the infeed is cut off, is pocketed, the times of which is regulated by the number of pockets or abutments formed on the steam engaging faces of the 35 casing and the piston and by reason thereof the expansive force is repeatedly utilized on the piston as the live steam impulses are intermittently admitted into the restricted space between the piston and casing, the 40 live steam impulses being regulated by the relative speeds of the valve and the piston, and by the number of cut offs and feed channels formed in the rotary controlling valve. Again, the valve mechanism is of 45 such character that it provides for practically continuous live steam impulses against the piston, by reason of first charging against the abutments at one side of the said piston and then against the abutments at the other side thereof, as well as 50 the continuous use of the expansive force, since the correlation of the pockets in the piston, the steam inlet, the pockets in the casing are so combined that at predetermined times, the live steam impulses are 55 either at one side of the rotary piston or at the other side, while the expansion of the prior charge is exerting itself on the down-going side of the piston, such operation not alone rendering the engine one of high 60 efficiency and speed, but also overcoming the sudden jerks and jars usually found in rotary engines. Furthermore, by reason of the gradually increasing depth of the pockets

in the piston peripheries and the gradually 65 decreasing depths of the pockets in the casing, the expanding force of the steam is always directed against the piston abutments forwardly and tangentially with respect to the piston axis, thus insuring a 70 maximum energy from a minimum expense of steam power.

While I have shown the piston with nine radial abutments and pockets, I desire it understood that the said number, as also 75 the number of pockets and abutments on the casing chamber may be increased or diminished and the valve may have a greater or less number of properly spaced cutoffs and steam channels without departing from 80 my invention or the scope of the appended claims. It should be noted that the abutments are oppositely arranged in both piston and casing.

It should be stated, the general construction of my present type of engine is also disclosed in my co-pending application, Serial No. 388239, filed August 12, 1907, allowed October 12, 1908. My present invention differs from what is shown in the said co-pending application in that the two series of steam passages and abutments are oppositely arranged, that is, in transverse alinement, instead of alternately arranged as described, shown and claimed in said other application. By reason of arranging the steam passages and abutments in transverse alinement or oppositely as stated, the live steam impact is applied at the same circumferential points on the piston in each of the passage ways.

Having thus described my invention, what I claim and desire to secure by Letters Patent, is:—

1. In a rotary engine, the piston and casing therefor, comprising two series of oppositely disposed annular abutments and oppositely disposed pockets in the casing, two series of peripheral pockets and abutments encircling the piston in co-operation with the 105 said annular abutments and pockets so as to form parallel steam passageways from the inlets to the exhausts and a valve operating to admit and cut off the steam to and from the said passageways alternately, so as to apply 110 live steam impulses direct from the boiler to one of the passageways as the expansive force of the cut off steam is applied in the other passageways.

2. A rotary engine, comprising a rotary 120 disk and a casing therefor, the disk and casing each having two series of annular abutments and pockets, the pockets and abutments of the two series being in transverse alinement.

3. A rotary engine, comprising a rotary disk and a casing therefor, the disk and the casing each having two series of annular

abutments and pockets, the pockets and abutments of the two series being in transverse alinement and of unequal number.

4. In a rotary engine in which is included a rotary disk and a casing therefor, the said disk and the casing each having two series of annular abutments and pockets and the casing having an inlet and an outlet; a rotary

controlling valve for the inlet having two series of alternately arranged pockets and cut 10 off.

P. F. HODGES.
